UNITED STATES PATENT OFFICE

JOHN J. G. C. SCHMIDT, OF JERSEY CITY, NEW JERSEY.

DESIGN FOR A WASHBOARD.

SPECIFICATION forming part of Design No. 30,187, dated February 14, 1899.

Application filed January 19, 1899. Serial No. 702,728. Term of patent 7 years.

► *To all whom it may concern:*

Be it known that I, JOHN J. G. C. SCHMIDT, a subject of the Emperor of Germany, and a resident of Jersey City, in the county of Hudson and State of New Jersey, have invented and produced a new and original Design for Washboards, of which the following is a specification, reference being had to the accompanying drawings, forming a part thereof.

The leading features of my design consist in a washboard presenting in face view a corrugated surface throughout a portion of the surface of the board and a group of perforations throughout another portion of the surface of the board.

In the accompanying drawings, Figure 1 is

a view of the washboard in face elevation, and Fig. 2 is a view in side or edge elevation.

A represents the corrugated portion of the face of the board, and B represents the group of perforations.

What I claim is—

The design for a washboard substantially as herein shown and described.

In testimony that I claim the foregoing as my invention I have signed my name, in presence of two witnesses, this 18th day of January, 1899.

JOHN J. G. C. SCHMIDT.

Witnesses:

FREDK. HAYNES,

EDWARD VIESER.
